(57) **CLAIM**

The ornamental design for a drill bit, as shown and described.

DESCRIPTION

FIG. 1 is a bottom, right-side perspective view of a drill bit showing our new design;

FIG. 2 is a bottom, left-side perspective view thereof;

FIG. 3 is a top, right-side perspective view thereof;

FIG. 4 is a front elevational view thereof;

FIG. 5 is a rear elevational view thereof;

FIG. 6 is a left side plan view thereof;

FIG. 7 is a right side plan view thereof;

FIG. 8 is a top plan view thereof; and,

FIG. 9 is a bottom plan view thereof.

The broken lines (short dash-short dash-short dash) in FIGS. 1-9 show portions of the drill bit that form no part of the claimed design. The boundary lines (long dash-short dash-long dash) in FIGS. 1-9 are for the purpose of showing the bounds of the claimed design and form no part thereof.
